[57] CLAIM

The ornamental design for a serving tray, as shown and described.

DESCRIPTION

FIG. 1 is a perspective view of a serving tray showing our new design;

FIG. 2 is a side elevational view thereof, the side opposite being a mirror image;

FIG. 3 is a bottom plan view thereof;

FIG. 4 is a front elevational view thereof;

FIG. 5 is a rear elevational view thereof;

FIG. 6 is a cross-section taken on line 6—6 of FIG. 2 on an enlarged scale;

FIG. 7 is a cross-section taken on line 7—7 of FIG. 2 on an enlarged scale; and

FIG. 8 is a cross-section taken on line 8—8 of FIG. 2 on an enlarged scale.
